Primary Examiner—A Hugo Word*Assistant Examiner*—Doris V. Coles*Attorney, Agent, or Firm*—Timothy T. Tyson**[57] CLAIM**

The ornamental design for a bottle holder, as shown and described.

DESCRIPTION

FIG. 1 is a front elevational view of a bottle holder showing my new design;

FIG. 2 is a left side elevational view thereof, holding a bottle shown in dotted outline;

FIG. 3 is a right side elevational view thereof;

FIG. 4 is a top plan view thereof;

FIG. 5 is a bottom plan view thereof; and,

FIG. 6 is a rear elevational view thereof.

The bottle shown in dotted outline in FIG. 2 is not part of the claimed design.
